UNITED STATES PATENT OFFICE.

FERDINAND THUN, OF WYOMISSING, PENNSYLVANIA, ASSIGNOR TO
TEXTILE MACHINE WORKS, INCORPORATED, OF WYOMISSING,
PENNSYLVANIA.

SHOE-LACING.

No. 852,747.

Specification of Letters Patent.

Patented May 7, 1907.

Application filed April 29, 1905. Serial No. 268,037.

To all whom it may concern:

Be it known that I, FERDINAND THUN, a citizen of the United States, residing in Wyomissing, in the county of Berks and State of Pennsylvania, have invented certain new and useful Improvements in Shoe-Lacings, of which the following is a specification.

My invention relates to braided fabrics and my main object is to produce an improved integrally formed braid such as a shoe lacing, which will have different portions thereof varied in texture and form to better adapt the article as a whole to its intended use. Thus for low shoes where it is desired to tie the ends of the lacing into an ornamental bow requiring a considerable width of the ends of the lacing, I provide for securing such required end width, in the first place, without incurring the inconvenience in service incident to maintaining such width in the intermediate portion of the lacing; and in the second place, with an increased compactness and strength of structure at such intermediate portion secured by compacting the fabric crosswise and lengthwise at such portion whereby the latter is not only adapted to be more easily inserted in the shoe eyelets, but is also adapted to better withstand the strain and wear to which it is subjected and to present a less bulky appearance than would the greater width required for the bow or tie portion!

The desired object is attained mainly by tightening or loosening the texture as required during the braiding operation by varying the take-off so as to produce at desired portions of the braid a relatively tight compacted structure whereby a given amount of material is employed in a reduced width and length of the fabric as compared with an adjoining portion, and in some cases by simultaneously changing the form of the braid from flat to tubular and thereby doubling the narrowed portion of the fabric.

The invention is more fully described in connection with the accompanying drawing and is specifically pointed out in the claims.

Figure 1 is a general view of a shoe-lacing embodying my invention in preferred partly tubular form. Fig. 2 is an enlarged fragmentary view including part of a wide-end

portion and part of the intermediate narrowed portion, and indicating a similar plain-braid structure but different compactness thereof in the different portions. Fig. 3 shows a modification in which the narrowing is effected merely by varying the closeness of the texture.

In the shoe-lacing shown in the drawing the intermediate portion 1 between the end portions 2-2, having the terminal tips 3 is evidently subjected to greater strains and wear because of the pull thereon required to tightly draw together the shoe upper and of the friction involved in sliding it through the several shoe eyelets under such pulling strain. It is evidently desirable also that such intermediate portion be of less spread or bulk than the ornamenteally tied end portion, both because of the greater ease and reduced wear with which it may in such cases be tightly drawn through the eyelets and because of the neater appearance of the stretched lacing between the vamps. My invention therefore aims to provide both increased strength and wearing quality, and decreased spread or bulk, in such intermediate portion 1, as compared with the end portions 2-2. These results are mainly secured, as indicated both in Fig. 2 and Fig. 3, by making the intermediate portion 1 of closer texture than the end portions 2-2, the same number of threads being continuously employed in braiding all portions of the fabric but said threads being materially compacted or tightly closed together in the intermediate portion 1 as compared with the end portions 2-2, as clearly indicated in the showings of thread crossings, shown at 3 and 4 respectively.

In Figs. 1 and 2 a further narrowing and strengthening of the intermediate portion 1 is effected by changing the cross-section thereof to a flattened tubular form thus doubling the thickness thereof and halving the width as compared with the simpler construction shown in Fig. 3, but without changing the amount of material employed in a given length of the fabric; which amount of material is in each case considerably greater than that employed in an equal length of the loosely plaited flat end portion 2-2.

The particular means which I employ in producing my improved article of manufacture forms no part of the present invention

and is made the subject matter of a separate application, Serial No. 316,237, filed May 11, 1906.

When the two ends of a low-shoe lace for instance are tied into a bow, the producing of the desired ornamental effect requires that they should be made wide and be readily spread-out when tied. Strength not being required in these end portions of the lace it is apparent that both for purposes of economy in material and effectiveness in appearance, a loose-braided texture is most desirable. On the other hand the portion that passes through the eyelets should be dense and closely braided so as to combine strength and neatness of appearance; and the preferred tubular cross-section of such portion is evidently best adapted to be passed through the eyelets easily, to provide the maximum of strength and minimum of wear, and to present a neat appearance. My invention provides for attaining these advantages in a very simple and highly satisfactory manner.

What I claim is:—

1. As a new article of manufacture an integrally formed braided-fabric lacing having the portion thereof intermediate of the tying-ends compacted crosswise and lengthwise of the fabric.

2. As a new article of manufacture an integrally formed braided-fabric lacing having relatively wide tying-end portions provided with terminal tips and narrowed intermediate portion for engaging the shoe eyelets. 30

3. As a new article of manufacture an integrally formed braided-fabric lacing having relatively wide flat tying-end portions provided with terminal tips and a narrowed tubular intermediate portion for engaging the shoe eyelets. 35

4. As a new article of manufacture an integrally formed braided-fabric lacing having relatively wide and loosely-braided flat tying-end portions and a tubular tighter-braided intermediate portion for engaging the shoe 40 eyelets. 45

5. As a new article of manufacture an integrally formed braided-fabric the braiding of the intermediate portion of which differs in tightness crosswise and lengthwise from that 50 of the end portions.

In testimony whereof, I affix my signature, in the presence of two witnesses:

FERDINAND THUN.

DISCLAIMER.

852,747.—*Ferdinand Thun*, Wyomissing, Pa. SHOE-LACING. Patent dated May 7, 1907. Disclaimer filed December 11, 1914, by *The Narrow Fabric Co.*, assignee, by mesne assignments.

Enters this disclaimer—

“To that part of the claim in said specification which is in the following words, to wit:

“2. As a new article of manufacture an integrally formed braided-fabric lacing having relatively wide tying-end portions provided with terminal tips and narrowed intermediate portion for engaging the shoe eyelets.

“3. As a new article of manufacture an integrally formed braided-fabric lacing having relatively wide flat tying-end portions provided with terminal tips and a narrowed tubular intermediate portion for engaging the shoe eyelets.”
